UNITED STATES PATENT OFFICE.

RICHARD BLUM, OF BERLIN, GERMANY.

CLOTHES-HANGER.

No. 895,615.

Specification of Letters Patent. Patented Aug. 11, 1908.

Application filed May 28, 1908. Serial No. 435,512.

To all whom it may concern:

Be it known that I, RICHARD BLUM, a citizen of the Empire of Germany, residing at Berlin, Germany, have invented certain new and useful Improvements in Clothes-Hangers, of which the following is a full, clear, and exact description.

This invention relates to clothes hangers and the like of the type wherein lateral arms 10 are adapted to telescope into a central portion, the object of the invention being to provide a clothes hanger which can be readily folded to occupy only a small space and thus be easily packed.

According to this invention the gripping members, hooks or holders on the under side 15 of the hanger are positively connected to the lateral arms so that they are folded up and opened out to assume an operative position according as the lateral arms are moved in or 20 out. Similarly the hook whereby the hanger as a whole is suspended is positively connected to the telescopic lateral arms so that it is folded into a plane approximately parallel to 25 that of the latter when the lateral arms are telescoped, the hook being brought into a vertical position when the lateral arms are opened out. The lateral arms are preferably provided with suitable pawls or the like where- 30 by they are locked in their open position.

One form of clothes hanger for gentlemen's clothes constructed in accordance with this invention is illustrated by way of example in the accompanying drawings.

Figure 1 is a side elevation, partly in section on the line 1—1 of Fig. 2 and Fig. 2 is an inverted plan of the hanger in its operative position, the holders on the underside thereof being removed. Fig. 3 is a side elevation 35 partly in section showing the hanger folded up. Fig. 4 is a longitudinal section on an enlarged scale of one of the lateral arms. Fig. 5 is a cross section on the line 5—5 of Fig. 4, and Fig. 6 is a detail view of a hook which 40 may be substituted for the holders shown in Figs. 1 to 3 when the apparatus is used for suspending ladies' dresses.

In the construction illustrated the clothes hanger comprises a hollow central portion 1 45 closed at the bottom by a plate 2 suitably connected to it and adapted to guide in the wellknown manner the telescopic or otherwise foldable lateral arms 3. At both ends of the central portion 1 are arranged on the 50 plate 2 holders 4 rotatable about pins 5. These holders 4, or hooks when the latter are

employed as shown in Fig. 6, are adapted to suspend or grip such articles of clothing, as trousers, jackets etc., and may be of various constructions to suit the class of garment it is 60 desired to hang up.

The upper ends of the holders 4 are connected by means of pivoted links 6 to blocks 7 which are free to slide in slots or guides 8 formed in the bottom plate 2. The inner 65 ends of the lateral arms 3 are also provided with slide blocks 9 mounted in guides 10 in the plate 2 these blocks limiting the outward and inward movement of the arms 3. The lateral arms 3 are moreover each provided 70 with a projection or stop 11 which, when the arms are being moved inwards, in the direction of the arrow in Fig. 1 strike the slide blocks 7 carried by the arms 3 and thus cause the links 6 to fold the holders 4 into the position shown in Fig. 3. At the same time the hook 13 whereby the hanger as a whole is suspended, is rotated about its pivot pin 12 and is also folded over, the shank of the hook 13 being positively connected by means of a 75 link 14 to one of the slide blocks 7. The head of the hook 13 is preferably made to rotate relative to its shank.

When the lateral arms 3 are pulled out, stop pins 15 which project laterally therefrom strike the slide blocks 7 of the rods 6 and cause the latter to bring the holders 4 into the operative position in Fig. 1. The lateral arms 3 are preferably locked in their open or operative position by means of spring 90 pawls 16 mounted on the under side 2 at both ends of the central part 1 these pawls engaging corresponding notches 17 on the lower face of each arm 3.

Before the lateral arms 3 can be closed, the 95 spring pawls 16 must of course be made to disengage the notches 17 by being pressed down, unless the arrangement is made in such a manner that, on pushing the arms in, the said pawls are automatically disengaged. 100

As will be seen from the foregoing, the clothes hanger can be folded up by a single operation namely by pushing in the lateral arms 3 both the hook 13 and the holders 4 being thereby folded down so that the whole 105 device occupies but a very small space. The central portion 1 is preferably provided on its upper face with a recess corresponding in shape and size with the hook 13 which it is intended to receive when the hanger is folded 110 the upper surface of the device when folded being thus perfectly flat.

It will be understood that the individual parts of the clothes hanger described may be modified in various ways to suit the kind of garments to be suspended without departing 5 from the spirit of this invention, thus a skirt holder of suitable construction may be substituted for the holders 4 or hooks 18.

What I claim is:—

1. In a clothes hanger the combination 10 with lateral arms adapted to telescope into a central portion, of holders pivotally mounted on the latter and an operative connection between the lateral arms and the holders.
2. In a clothes hanger the combination 15 with a central portion, of lateral arms adapted to telescope therein, of a suspension hook

and of means for positively connecting said holders and said hook to the lateral arms.

3. In a clothes hanger the combination 20 with a central portion, of lateral arms adapted to telescope therein, of a suspension hook, of means for positively connecting said holders and said hook to the lateral arms, and of catches maintaining the suspension hook and the holders in their extended position.

In testimony whereof, I have hereunto set my hand in the presence of two subscribing witnesses.

RICHARD BLUM.
